US0D1061025S

(12) **United States Design Patent** (10) **Patent No.:** **US D1,061,025 S**
(45) **Date of Patent:** **** Feb. 11, 2025**

(54) **STORAGE BOX**

(71) Applicant: **TAIZHOU SUKK TECHNOLOGY CO., LTD**, Zhejiang (CN)

(72) Inventor: **Shuangshuang Xiao**, Zhejiang (CN)

(73) Assignee: **TAIZHOU SUKK TECHNOLOGY CO., LTD**, Taizhou (CN)

(**) Term: **15 Years**

(21) Appl. No.: **29/949,612**

(22) Filed: **Jun. 27, 2024**

(51) LOC (15) Cl. **06-04**

(52) U.S. Cl.

USPC **D6/667**; D3/294

(57) **CLAIM**

The ornamental design for a storage box as shown.

DESCRIPTION

FIG. 1 is a front, left, and top perspective view of a storage box, showing my design;

FIG. 2 is a rear, right, and bottom elevation view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

1 Claim, 8 Drawing Sheets
